Primary Examiner — Kevin K Rudzinski*Assistant Examiner* — Clare Ann Gannon(74) *Attorney, Agent, or Firm* — Christopher A. Proskey; BrownWinick Law Firm(57) **CLAIM**

The ornamental design for a drapery rod, as is shown.

DESCRIPTION

FIG. 1 is a rear elevation of a drapery rod;

FIG. 2 is a top plan view thereof;

FIG. 3 is a front elevation view thereof;

FIG. 4 is a top plan view thereof;

FIG. 5 is a left side elevation view thereof;

FIG. 6 is a rear perspective view thereof;

FIG. 7 is a top perspective view thereof;

FIG. 8 is a front perspective view thereof; and,

FIG. 9 is a bottom perspective view thereof.

The break lines shown in FIGS. 1-4 and 6-9 symbolize breaks in the length of the article in which the claimed design is embodied. The appearance of any portion of the article between the break lines forms no part of the claimed design.

1 Claim, 9 Drawing Sheets(56)
